GAS BURNER AND MIXING TUBE
CONSTRUCTION

Napoleon E. Hill, Otto J. Ress, and Frank J. Nunlist, Jr., Milwaukee, Wis., assignors to L. J. Mueller Furnace Company

Application April 4, 1946; Serial No. 659,629

3 Claims. (Cl. 158—99)

1

This invention relates to improvements in gas burner and mixing tube constructions.

A general object of the invention is to provide an improved gas burner and mixing tube so constructed as to eliminate extinction noise and "flashback" characteristics.

In connection with the operation of gas burners having conventional mixing tubes associated therewith, considerable difficulty has been experienced when burning gas with high ignition velocity characteristics. A very pronounced objection has been the extinction noise and "flashback" characteristics common to the operation of gas burners formed with conventional mixing tubes. It is the theory that in such structures the extinction noise and "flashback" characteristics are caused by the following conditions: When the supply of gas to the burner is shut off, there is, of course, residual gas in the piping between the shut-off valve and the burner ports or orifices. Upon the closing of the gas supply shut-off valve, the quantity of gas within the device and reaching the burner ports is gradually reduced. Consequently, there is less energy in the gas streams leaving the burner ports and the quantity of primary air within the mechanism is consequently reduced. However, the ratio of primary air to gas greatly increases. Up to a definite ratio of primary air to gas, the ignition velocity of the combustible mixture increases and a situation attains wherein after the gas supply shut-off valve to the mixing tube is closed, the ignition velocity increases until it is greater than the velocity of the primary air-gas mixture in the burner ports. At such time the flame will travel back or recede through the burner ports into the burner head and will ignite the primary air-gas mixture therein. If there is a sufficient volume of the combustible mixture within the mechanism, an explosion or extinction noise results.

With the foregoing explanation in mind, the present invention aims at eliminating objectionable explosions and extinction noises inherent to the operation of conventional gas burner mechanisms by providing a gas burner and mixing tube construction wherein the mixing tube communicating with the burner head has associated therewith a trap which extends above the level of the burner ports. Inasmuch as the air-gas mixture within the burner head has a specific gravity less than that of air, with the improved elevated trap construction associated with the mixing tube, after the gas supply valve has been shut off, the air-gas mixture in the burner head

2

tends to flow into and rise to the highest point in the trap. Such trapped air-gas mixture within the trap then tends to block or counteract the normal flow of air admitted through an air valve in a lower portion of the trap, and by blocking the flow of additional air, the "flashback" or extinction noise tendency of the burner is overcome.

A more specific object of the invention is to provide a gas burner and mixing tube construction wherein the mixing tube, remote from the burner head, carries an elevated cylindrical trap which has located therein below its top, air and gas inlets.

15. A further object of the invention is to provide a gas burner and mixing tube construction wherein the mixing tube has a portion of substantial length at an elevation above the elevation of the burner gas ports, and which terminates, remote 20 from the burner, in a trap of relatively large volume and projecting above the level of the burner gas ports, said elevated portions of the mixing tube and trap being adapted to receive a light air-gas mixture and to hold the same, 25 under certain conditions, as a curtain between the primary air and gas inlets and the burner ports.

30. A further object of the invention is to provide a gas burner and mixing tube construction of such formation that the primary air and/or the primary air-gas mixture must travel upwardly and then downwardly before reaching the burner head, with the uppermost point of flow being substantially above the plane of the burner ports.

35. A further object of the invention is to provide a gas burner and mixing tube construction which is very simple, is easy to install, service and regulate, is relatively inexpensive, which functions efficiently, and which is well adapted for the purposes described.

40. With the above and other objects in view, the invention consists of the improved gas burner and mixing tube construction, and its parts and combinations as set forth in the claims, and all equivalents thereof.

In the accompanying drawing in which the same reference characters indicate the same parts in all of the views:

45. Fig. 1 is a side view, partly in longitudinal vertical sectional view of the improved gas burner and mixing tube construction with an outer end portion of the burner head being broken away;

50. Fig. 2 is a plan view of the gas burner and mixing tube; and

55. Fig. 3 is a fragmentary inverted plan view of

that portion of the apparatus which includes the mixing tube and trap.

Referring now more particularly to the drawing, it will be observed that a hollow gas burner is indicated generally by the numeral 8. The burner head may be of any desired accepted shape and may take the form of a T, as illustrated. In top wall portions of the burner head there are a plurality of burner port stools 9 with drilled gas ports or orifices 10 therethrough. The particular type of gas port referred to is merely by way of illustration and the burner head may, within the purport of the invention, be formed with any conventional type of gas port. The inner end of the burner head 8 is curved upwardly and the gas entrance end therein is surrounded by an annular shoulder 12 adapted to have seated thereon the adjacent end of a mixing tube, indicated generally by the numeral 13. The end portion of the mixing tube referred to is securely connected to the shoulder 12 of the burner head by any suitable means which will provide a gas tight joint.

The mixing tube 13 is venturi-like in formation with the end adjacent the burner head being enlarged and curved downwardly to engage the upturned end of the burner head. The major extent of the mixing tube is horizontal and the same extends at an elevation substantially above the plane of the burner ports 10. The composite structure which includes the burner head 8 and the mixing tube 13 is of goose neck formation.

The outer reduced end of the mixing tube 13 has formed integral therewith a cylindrical casing 14 whose longest dimension is in a vertical plane. The closed upper end of the casing 14 is disposed somewhat above the mixing tube 13. The hollow interior of the casing 14 therefore provides a trap for the purpose hereinafter to be explained, with the interior of the casing having an outlet to the mixing tube somewhat below the top of the casing.

On the side wall of the casing 14 opposite the connection of the casing with the end of the mixing tube 13 is an apertured boss 15 having secured therethrough a gas supply nipple 16 which is in connection with an outwardly extending gas supply pipe 17. The discharge end of the gas nipple 16 is so arranged relative to the casing 14 that it discharges thereinto generally in alignment with the outer end of the mixing tube 13 and the axis of said mixing tube.

The lower open end of the cylindrical casing 14 is provided with spaced radial webs 18 adapted to cooperate with an air shutter 19, said webs having a central boss 20 to which is attached by means of a bolt 21, the adjustable air shutter 19, previously referred to. The adjustable air shutter 19 is of the type which may be turned circularly to more or less close or open the spaces between the fixed webs 18 for the purpose of controlling the amount of primary air admitted into the trap forming casing 14.

Depended from a transverse portion of the burner head 8 is a tapped flange 22 which may be used for the attachment of pilot light equipment. From Fig. 1 it will be observed that the mixing tube 13 provides a gas carrying conduit which is above the level of the burner ports 10. Likewise, the major portion of the interior of the casing 14 is above the level of the burner ports. The gas supply nipple 16 is arranged to supply gas into the apparatus in a stream which is directed toward the open end of the mixing tube 13 and co-axially with said mixing tube.

The point of introduction of the gas is at an elevation above the plane of the burner ports 10. On the other hand, the primary air enters the interior of the casing 14 at a considerably lower elevation and the direction of flow of incoming primary air is at right angles to the direction of flow of incoming gas.

If, as is conventional in the operation of a gas burner, an automatic shutoff valve (not shown) terminates gas flow from the gas supply pipe 17 and nipple 16 into the casing 14, a condition will thereafter exist where only primary air enters the casing 14 and flows into the mixing tube 13. The air-gas mixture within the apparatus will obviously become diluted. For a time this residual combustible mixture within the apparatus will flow into the hollow burner head 8 and will exhaust through the burner ports 10 where combustion takes place. Eventually, a condition will develop wherein the ignition velocity becomes greater than the velocity of the air-gas mixture at the burner ports. This induces a condition wherein there would ordinarily be a tendency for the flame to travel back into the burner head and ignite the air-gas mixture therein, resulting in a "flashback" or extinction noise. The present improvements prevent this highly objectionable contingency because the air-gas mixture in the burner head, being lighter than air, will tend to flow back through the burner head and rise into the elevated portions of the mixing tube 13 and casing 14, said portions being above the plane of the burner ports. Consequently, this arrangement serves to establish a curtain of light air-gas mixture within said elevated portions of the apparatus. This light air-gas mixture curtain is interposed between the primary air inlet in the lower end of the casing 14 and the gas ports 10 and thereby serves to block the normal flow of primary air which continues to enter the casing 14, preventing the incoming primary air from further diluting the residual combustible gas in that portion of the apparatus adjacent which the ignition occurs, preventing "flashbacks" and extinction noises.

It is to be noted that the casing 14 at the outer end of the mixing tube 13 provides a relatively large capacity, trap or reservoir and under normal conditions it enhances the admission of primary air and gas which are admitted at spaced points and in a manner so that the respective streams are generally at right angles to each other.

From the foregoing description, it will appear that the improved gas burner and mixing tube construction is both simple and novel, eliminates objections inherent to conventional gas burner and mixing tube constructions, and is well adapted for the purposes described.

What we claim as our invention is:

1. A composite gas burner head and mixing tube assembly of goose neck formation wherein the mixing tube portion extends horizontally at an elevation substantially above the burner head portion, the latter being parallel to the major extent of the mixing tube and being provided with burner ports in the top portion thereof, a hollow casing entered by the outer end of the mixing tube portion and extending above the planes of the mixing tube and burner head portions, and spaced apart means entering right angularly separated wall portions of the casing for admitting primary air and gas in a manner so that the primary air stream enters said casing at substantially right angles to the entering gas stream.

2. In a gas burner construction, a hollow elongated burner head formed with upwardly opening burner ports in the top portion thereof, a mixing tube having an elongated rectilinear portion and an elbow portion, the latter portion being connected to the burner head so as to open into the interior of the latter at substantially a right angle to the axial line of the burner head and disposing the rectilinear portion of the mixing tube at an elevation above the plane of the burner ports, a hollow casing carried by the outer end of the rectilinear portion of the mixing tube and communicating therewith and having a portion extended substantially above said rectilinear portion and above the plane of the burner ports, means for admitting primary air into said casing below the axial line of the mixing tube, and means for admitting gas into said casing at a point above the line of the burner ports, whereby the gas-air mixture must flow through the elevated mixing tube and then downwardly through the elbow portion thereof and then longitudinally through the burner head before being upwardly exhausted through the burner ports.

3. In a gas burner construction, a hollow, elongated, horizontally disposed burner head formed with upwardly opening burner ports in the top portion thereof, a mixing tube having an elongated rectilinear portion and an elbow portion, the latter being connected to and in communica- 30

tion with the burner head and disposing the rectilinear portion of the mixing tube parallel with and above the burner head, the outer end portion of the mixing tube being enlarged to form a chamber which depends below the axial line of the rectilinear portion of the mixing tube, means for admitting primary air into a lower portion of said chamber, and means for admitting gas into a higher portion of said chamber, the arrangement being such that the gas-air mixture flows through the elevated mixing tube and then downwardly and into the burner head for discharge in an upward direction through the burner ports.
